UNITED STATES PATENT OFFICE.

GEORGE M. LINDSEY AND WILLIAM A. LINDSEY, OF LOS ANGELES, CALIFORNIA.

WATCH-GUARD.

1,027,487.

Specification of Letters Patent.

Patented May 28, 1912.

Application filed April 24, 1911. Serial No. 623,078.

To all whom it may concern:

Be it known that we, GEORGE M. LINDSEY and WILLIAM A. LINDSEY, both citizens of the United States, residing at Los Angeles, 5 in the county of Los Angeles and State of California, have invented a new and useful Watch-Guard, of which the following is a specification.

This invention relates to means for preventing 10 watches from being dislodged or stolen from the pocket, and the main object of the invention is to provide a simple and effective device for this purpose which will be of minimum cost and easily applied.

15 The accompanying drawings illustrate the invention, and referring thereto: Figure 1 is a front elevation of a watch with the guard thereon. Fig. 2 is a side elevation of the watch with the guard shown in section. 20 Fig. 3 is a vertical section of the guard. Fig. 4 is a plan view thereof.

The guard comprises an elastic member of soft rubber having a central perforation adapted to fit over the stem of a watch. 25 Said member is formed as a disk having a central projecting hub 1 provided with a bore or central opening 2, a peripheral enlarged portion or rim 3 and a relatively thin web portion 4 connecting said hub and rim, 30 said hub 1 projecting on both sides of the web flush with the enlarged rim portion 4

to provide spacing collars and said web portion 4 being sufficiently thin to give considerable elasticity and the rim portion 3 giving a relatively stiff periphery for engagement with the sides of the pocket.

The guard is attached to the watch by slipping it over the ring 7 and stem 8 of the watch, the hub 1 expanding or stretching in this operation and then contracting to bind 40 or grip the stem 8 firmly, said hub portion engaging between the body 5 of the watch and the collar 6 which supports the ring 7 of the watch.

What we claim is:

45 A watch guard comprising an elastic disk of soft rubber formed with an enlarged rim, a hub having a stem opening and projecting on both sides of the disk so as to provide inner and outer spacing collars adapted to 50 fit around the stem of a watch, between the body and the collar thereof, and a thin web between the middle portion of the hub and the enlarged rim.

In testimony whereof, we have hereunto 55 set our hands at Los Angeles, California, this 15th day of April, 1911.

GEORGE M. LINDSEY.
WILLIAM A. LINDSEY.

In presence of—

ARTHUR P. KNIGHT,
FRANK L. A. GRAHAM.
